UNITED STATES PATENT OFFICE

156,317

COMBINED TAILLIGHT AND TOOL KIT

Jacob Bromberg, New York, N. Y.

Application February 11, 1949, Serial No. 796

Term of patent 3½ years

(Cl. D90—3)

To all whom it may concern:

Be it known that I, Jacob Bromberg, a citizen of the United States of America, residing in New York, county of New York, and State of New York, have invented a new, original, and ornamental Design for a Combined Taillight and Tool Kit, of which the following is a specification, reference being had to the accompanying drawing, forming part thereof.

Fig. 1 is a front perspective view of a combined taillight and tool kit showing my new design.

Fig. 2 is a rear perspective view thereof.

I claim:

The ornamental design for a combined taillight and tool kit, substantially as shown.

JACOB BROMBERG.
